UNITED STATES PATENT OFFICE.

NORBIT O. MEGORDEN, OF CLEARWATER, WASHINGTON.

TOY.

Application filed April 4, 1922. Serial No. 549,609.

To all whom it may concern:

Be it known that I, NORBIT O. MEGORDEN, a citizen of the United States, residing at Clearwater, in the county of Jefferson and 5 State of Washington, have invented new and useful Improvements in Toys, of which the following is a specification.

This invention relates to improvements in toys and has particular reference to that 10 type of toy adapted to be drawn after the person by a string or other drawing member.

The principal object of this invention is to produce a toy which will simulate the movements of an animal.

15 Another object of this invention is to produce a toy which is attractive in appearance, cheap to manufacture and one which may be utilized as a vehicle upon which a child may be drawn if desired.

20 Other objects and advantages will be apparent during the course of the following description.

In the accompanying drawings forming a part of this specification, and in which like 25 numerals are employed to designate like parts throughout the same,

Fig. 1 is a side elevation of my toy which represents a crocodile.

Fig. 2 is a horizontal cross section of my 30 device showing the working parts thereof, and

Fig. 3 is a vertical cross section of my toy.

I am aware of the fact that toys have been 35 made which represent animals, but these representations as far as I am aware of do not simulate all the movements of the animal, where in my device I have performed this function and consequently a child playing with the same secures more enjoyment.

40 In the accompanying drawings wherein for the purpose of illustration is shown a preferred embodiment of my invention, the numeral 5 represents the body portion of the animal which is formed with a hollow

45 interior 6. A tail 7 which may be hollow or solid as conditions permit is pivoted at 8 and is adapted to swing in the various dotted line positions shown in Figure 2. This tail may be attached by a dovetail as shown in 50 Figure 1 or may be merely lapped. I pro-

vide an under jaw 9 integral with the body of the animal and an upper jaw 11 pivoted as at 12, the ends of the pivot forming the eyes as shown at 13. At 14 I have shown a tongue which is adapted to slide between 55 guides 16 and 17 (see Fig. 2). This tongue is attached by a rod 18 to a crank 19 supported as at 21 and 22 in the sides of the body portion 5. Wheels 23 and 24 are secured upon the crank 19 and through their 60 contact with the surface over which the toy is being drawn causes the crank 19 to revolve. This revolving causes the tongue 14 through its connection 18 to move inwardly and outwardly between the guides 16 and 65 17. At the same time this movement is taking place a rod 26 contacting the underside of the crank 19 transmits movement to the upper jaw 11 to which it is connected as best shown in Figures 2 and 3. A link 27 70 connects the crank 19 with an eye bolt 24 secured in the tail 7 at a point on the opposite side from the pivot 8. It will thus be seen that as the wheels 23 and 24 are revolved motion will be transmitted to the 75 crank 19 which will through the connecting members 18 and 27 cause the tongue 14 to move inwardly and outwardly and will cause the tail 7 to hinge on its pivot and thereby simulate the wagging motion of a crocodile's 80 tail. At the same time the contact of the rod 26 with the underside of the crank 19 will cause the jaw 11 to open which opening will take place as the tongue moves forwardly and will close as the tongue is drawn 85 into the mouth.

It is to be understood that the form of my invention herewith shown and described is to be taken as a preferred example of the same, and that various changes in the shape, 90 size and arrangement of parts may be resorted to without departing from the spirit of the invention or the scope of the subjoined claim.

Having thus described my invention, I 95 claim:

In a device of the character described, the combination of a body portion, a tail portion, said tail portion being pivoted to said body portion at one side thereof and at a 100

point near one end thereof, a jaw portion pivoted to said body portion at the opposite end from said tail portion so as to be capable of up and down movement, a crank mounted in said body portion, wheels secured to said crank, a tongue slidably supported on said body portion at a point be-

low said movable jaw, a rod connecting said tongue and said crank, a link connecting said tail and said crank, and a rod contacting the underside of said crank, said rod being secured to said jaw portion. 10

In testimony whereof I affix my signature.
NORBIT O/MEGORDEN.
